TIE HOLDER CONSTRUCTION

Frederick A. Bullock, Attleboro, Mass., assignor to Dolan & Bullock, Providence, R. I., a partnership consisting of Arthur S. Dolan, Frederick A. Bullock, and William G. Bennett

Application November 15, 1934, Serial No. 753,155

22 Claims. (Cl. 24—49)

My present invention relates to articles of jewelry, and has particular reference to tie holders which hold the tie in substantially fixed relation to a shirt, while permitting a limited movement with respect thereto.

It is the principal object of my invention to provide a tie holder which has a clamp releasably securable to the hem of a shirt front, and which has a loop portion slidably engaging the tie, this portion being movable with respect to the clamp.

It is a further object of my invention to provide a tie holder which is adjustable to slidably engage cravats of different widths.

With the above and other objects and advantageous features in view, my invention comprises a novel arrangement of parts more fully disclosed in the detailed description following, in conjunction with the accompanying drawings, and more specifically defined in the claims appended thereto.

In the drawing,

Fig. 1 is a fragmentary view of a tie, with the novel tie holder positioned thereon;

Fig. 2 is a plan view of the novel tie holder;

Fig. 3 is a side view thereof, the claim being broken away; and

Fig. 4 is a plan view of a modified construction.

30 The novel tie holder comprises a clamp which is removably securable to the hem of a shirt front, and which may be of any desired construction; a preferred construction is formed of a rear loop of wire 10 having a connector end

35 11 and a transverse cross bar 12 mounted between the sides and a front element 13, which may also be of wire, having one end 14 extending rearwardly and locked to the connector end 11, as by a connector tube 15, the front element

40 being formed or shaped to provide an eye 16, 17 at each end thereof. If desired, a single length of wire may be shaped to provide both the rear loop and the front element.

An endless flexible member 18, such as a chain is threaded through the two eyes so as to depend from the clamp, as indicated in Fig. 2, whereby a tie may be inserted through the chain to retain the tie in relatively fixed relation to the shirt, while permitting a slight lateral movement and a sufficient amount of vertical movement of the tie to accommodate itself to the body movements of the wearer. This movement is greatly assisted by the endless character of the chain and its mounting, as the entire chain

may shift, whereby catching of the tie between chain links and possible tearing is lessened.

If desired, the front element may be in sections, as indicated in Fig. 4, the front element 19 terminating in a connector 20 which may be 5 in the form of a tube secured thereto, in which a second front element 21 is slidably mounted, the front element 19 having an eye 22 at the outer end, and the second front element 21 having an eye 23 at its outer end, and having its 10 inner end 24 bent, or enlarged, so as to prevent accidental removal from the connector 20.

It is thus evident that the novel tie holder includes a clamp which is detachably engageable with the hem of a shirt front, and which has 15 an endless flexible member such as a chain connected thereto to provide a depending loop portion movable with respect to the clamp, the width of the loop being adjustable to fit different widths of ties. Moreover, the construction described may be readily adapted for other articles 20 of jewelry, such as brooches and the like.

Although a preferred construction of clamp has been described, any suitable type of clamp 25 may be used; and any construction of chain or flexible member, may be used, within the spirit and the scope of the invention as defined in the appended claims.

I claim:

1. In combination, a clamp adapted to releasably engage a garment part, and an endless flexible member slidably extending through spaced parts of said clamp and depending therefrom to provide a loop portion. 30

2. In combination, a clamp having spaced 35 members resiliently urged towards each other to releasably engage a garment part and having spaced eyes, and a flexible member slidably extending through said eyes.

3. In combination, a clamp adapted to releasably engage a garment part and having spaced eyes, and an endless flexible member 40 slidably extending through said eyes.

4. In combination, a clamp having spaced 45 members resiliently urged towards each other to releasably engage a garment part and having spaced eyes, and a flexible member slidably extending through said eyes and depending therefrom to provide a loop portion.

5. In combination, a clamp adapted to releasably engage a garment part and having spaced eyes, and an endless flexible member 50 slidably extending through said eyes and depending therefrom to provide a loop portion.

6. In combination, a clamp adapted to releas-

- ably engage a garment part, and an endless chain slidably extending through spaced parts of said clamp and depending therefrom to provide a loop portion.
5. 7. In combination, a clamp having spaced members resiliently urged towards each other to releasably engage a garment part and having spaced eyes, and a chain slidably extending through said eyes and depending therefrom to provide a loop portion.
10. 8. In combination, a clamp adapted to releasably engage a garment part and having spaced eyes, and an endless chain slidably extending through said eyes and depending therefrom to provide a loop portion.
15. 9. In combination, a clamp comprising a rear portion and a front bar, spaced eyes positioned on said front bar, and an endless flexible member slidably mounted in said eyes.
20. 10. In combination, a clamp comprising a rear portion and a front bar, said front bar including parts relatively movable to extend and contract the length of the bar, spaced eyes positioned on said relatively movable parts, and a flexible member extending between said eyes, whereby the spacing between the eyes is adjustable.
25. 11. In combination, a clamp comprising a rear portion and a front bar, spaced eyes positioned on said front bar, and a chain slidably mounted in said eyes.
30. 12. In combination, a clamp comprising a rear portion and a front bar, said front bar including parts relatively movable to extend and contract the length of the bar, spaced eyes positioned on said relatively movable parts, and a chain extending between said eyes, whereby the spacing between the eyes is adjustable.
35. 13. In combination, a clamp having a front bar, said bar comprising two elements adjustably slidable relative to each other to extend and contract the length of said bar, eyes positioned on said elements, and a flexible member extending between said eyes.
40. 14. In combination, a clamp having a front bar, said bar comprising two elements adjustably movable relative to each other to extend and contract the length of said bar, eyes positioned on said elements, and a chain extending between said eyes.
45. 15. In combination, a clamp having a front bar, said bar comprising two elements adjustably movable relative to each other to extend and contract the length of said bar, eyes positioned on said elements, and an endless flexible member mounted in said eyes.
50. 16. In combination, a clamp having a front bar, said bar comprising two elements adjust-
- ably sildable relative to each other to extend and contract the length of said bar, eyes positioned on said elements, and an endless chain mounted in said eyes.
5. 17. A necktie holder comprising a clasp for connection with wearing apparel, and an endless flexible element having two bight portions supported at spaced points on the clasp and having spaced strands of a length greater than the distance between said spaced points and draped 10 below the bar, one above the other, to extend across a necktie in use.
15. 18. A necktie holder comprising a wearing apparel clasp provided with an eye at each end thereof, and an ornamental endless element flexible throughout its length slidably supported at spaced points in said eyes and forming separate strands each adjustable vertically toward and away from the other and vertically toward and away from the clasp.
20. 19. A necktie holder comprising a clasp for connection with a shirt and including a bar having an eye at each end thereof, and an ornamental endless chain of greater length than said bar and uniformly flexible throughout its length 25 and sildably extended at spaced points in its length through said eyes of the bar, said chain being endless and thus forming separate strands between the eyes, each of said strands being of a length greater than the length of the bar and 30 draped from the bar across the space between the eyes.
25. 20. A necktie holder comprising a clasp and an endless flexible element having running connection with the clasp and forming two flexible strands lengthwise of the clasp at lengthwise spaced points of the latter for disposition across the front of the necktie below the clasp and lengthwise of the latter, each of which strands may be lengthened by reason of said running 35 connections with a corresponding shortening of the other strand.
30. 21. A necktie holder comprising a clasp, and an endless member uniformly flexible throughout its length and having running connections at 40 spaced points thereof with lengthwise spaced points of the clasp.
35. 22. A necktie holder comprising a clasp having lengthwise spaced guides, and an endless flexible member extending at spaced points along one 45 side loosely through the guides of the clasp to form a loop having two strands extending between the guides, the strands forming between each other a tie receiving space, and both strands together forming between the same and the 50 clasp a second tie receiving space.

FREDERICK A. BULLOCK.
